C. K. HARRISON, JR., ET AL.

HOLDER FOR SCORING PADS

Filed Oct. 30, 1922

FIG. I.

FIG. 2.

FIG. 3.

FIG. 4.

WITNESS:

Robt R. Kitchel.

Louis Rodman Page, Jr. and
Charles K. Harrison, Jr.

BY
Frank S. Busser
ATTORNEY.

UNITED STATES PATENT OFFICE.

CHARLES K. HARRISON, JR., OF BALTIMORE, MARYLAND, AND LOUIS RODMAN PAGE, JR., OF PHILADELPHIA, PENNSYLVANIA.

HOLDER FOR SCORING PADS.

Application filed October 30, 1922. Serial No. 597,780.

To all whom it may concern:

Be it known that we, CHARLES K. HARRISON, Jr., and LOUIS RODMAN PAGE, Jr., citizens of the United States, residing at 5 Baltimore, county of Baltimore, and State of Maryland, and Philadelphia, county of Philadelphia, State of Pennsylvania, respectively, have invented a new and useful Improvement in Holders for Scoring Pads, 10 of which the following is a full, clear, and exact description, reference being had to the accompanying drawings, which form a part of this specification.

The object of our invention is to provide 15 a holder for scoring pads, such as, for example, are used for keeping score in playing auction bridge.

Heretofore it has been customary to keep the score, in playing bridge, on a pad or 20 tablet, which is kept on the table in a position convenient to the player who is keeping the score, the score being set down after each hand is played.

Frequently, during the play and especially 25 while the players are bidding their hands, it becomes desirable for the players to be informed as to the state of the score in order that they may take it into consideration in making their bids. With the means for 30 keeping the score heretofore used, the score cannot be readily seen by the players other than the score keeper, and when information is desired it is necessary to ask the score keeper, thus diverting his attention from 35 his hand, annoying the other players, and interrupting the play.

In accordance with our invention, means 40 are provided for holding the score pad, which will so hold the pad as to allow the score to be readily set down on the completion of a hand and which at the same time will be adapted to so hold the score during the play as to make it available to all the players at a glance.

Having now indicated in a general way 45 the nature, purpose and advantage of our invention, we will now proceed to describe a preferred embodiment thereof with reference to the accompanying drawings, in 50 which:

Fig. 1 is a plan view of a score pad holder, embodying our invention, in position for scoring.

Fig. 2 is a plan view of the subject of Fig. 55 1 in position to display the score.

Fig. 3 is a sectional view on line 3—3 Fig. 2.

Fig. 4 is a sectional view on line 4—4 Fig. 1.

a is a pad holder, the lower end and a portion of the sides being provided with flanges *b*, which serve to retain the lower portion of the score pad *c*, while the upper end is bent over as at *d* to receive the upper end of the score pad. 60

The holder *a* is secured to the end of a carrier plate *e*, the sides of which are flanged, by means of pivots *f*, *f*, while springs *g*, *g* secured to the pivots and to the holder tend to retain the holder in a position extending at an angle to the carrier plate, as shown in Fig. 3. 65

The carrier plate is provided on its under side with an extension adapted to extend through an aperture in a base *h* and be bent around to extend parallel with the under side of the base to form a pivoted connection between the carrier and the base, and in its extension to form an arm *i*. A spring *j* secured to the end of the arm *i* extends to and is secured to the edge of the base adjacent one of its corners. 70 75 80

The edges of the base are turned down to form a support therefor and to space the base from a surface, as a table, upon which it is placed. A spring catch *k*, adapted to engage the pad holder, is provided at one end of the base. 85

In the use of the device, when the score is to be entered on the pad, the pad holder is down, against the action of springs *g*, *g*, to lie flat on the carrier and the carrier is positioned about its pivot, against the action of spring *j*, so that the upper end of the pad holder will be engaged by the catch *k*, which will retain the holder against the action of springs *g*, *g* and the carrier against the action of spring *j* on arm *i*. In such position, as shown in Figs. 1 and 4, the pad will be firmly supported and the device being positioned adjacent the player keeping the score, the score may be readily set down. 90 95

After the score has been set down, the player scoring releases catch *k* and under the influence of springs *g*, *g* the holder will move upwardly, clear of the catch, and extend at an angle to the carrier plate. At the same time, spring *j* acting on arm *i* causes the carrier plate to turn about its pivot, thus reversing the score pad, as shown in 100 105 110

Fig. 2, and making the score readily available to the other players. It will be obvious that the degree of reversal of the score pad may be regulated so that on release of the

5 catch the score pad will be positioned as to be conveniently observed by the players.

It will also be obvious that our invention may be applicable to the holding of score pads for use in scoring any game other 10 than bridge.

Having now fully described our invention, what we claim and desire to protect by Letters Patent is:

1. Means for holding score pads, comprising a base, a pad holder, means affording a connection between said pad holder and base, whereby said pad holder may be extended at an angle to said base and rotated relative thereto.

20 2. Means for holding score pads, comprising a base, a pad holder, and a horizontal pivot and a vertical pivot affording connection between said pad holder and the base, said pad holder being movable about 25 either of said pivots independently of the other.

3. Means for holding score pads comprising, in combination, a pad holder, a base, means adapted to position the pad holder 30 relative to the base for a display of the score to a plurality of players, and means for retaining the pad holder in a position substantially parallel to the base for entry of the score on a pad held thereby by one of the 35 players.

4. Means for holding score pads comprising, in combination, a base, a pad holder, and means adapted to rotate said holder in a plane substantially parallel to the base and 40 to position it to extend at an angle relative to the base.

5. Means for holding score pads comprising, in combination, a base, a carrier plate

pivoted vertically on said base, a pad holder pivoted horizontally on said carrier, and 45 means adapted to move said carrier and said pad holder on their respective pivots.

6. Means for holding score pads comprising, in combination, a base, a carrier plate pivotally mounted on the base, means adapted to rotate the carrier plate relative to the base, a pad holder pivotally mounted on the carrier plate, means adapted to move said holder into a plane at an angle to the plane of the base, and means adapted to prevent 50 55 rotation of the carrier or movement of the holder.

7. Means for holding score pads comprising, in combination, a base, a carrier plate pivotally mounted on said base, an arm attached to the pivot, a spring extending between said arm and the base adapted when under tension to rotate the carrier in a plane parallel to the plane of the base, a pad holder pivotally mounted on said carrier 60 65 plate, a spring adapted when under tension to move the holder to extend at an angle to the base, and means carried by the base adapted to engage the holder and retain the holder and carrier plate in a position with 70 the said springs under tension.

8. Means for holding score pads comprising, in combination, a base, a carrier plate vertically pivoted to the base, means adapted to rotate the carrier plate about its pivot, a pad holder horizontally pivoted to the carrier plate, and means adapted to move the pad holder about its pivot.

In testimony of which invention, we have hereunto set our hands, at Baltimore, Md., 80 on this twenty-fifth day of October, 1922, and at Philadelphia, Penna., on this twenty-fourth day of October, 1922.

CHARLES K. HARRISON, JR.
LOUIS RODMAN PAGE, JR.
